LOAD BINDER

Thomas H. Edelblute, Reynoldsville, Pa.

Application June 15, 1948, Serial No. 33,059

2 Claims. (Cl. 254—164)

1

This invention relates to a load binder of the type employed to apply a pulling force to the ends of a chain or the like which is used to bind a load such as lumber in position, for example, while being transported.

In the transportation of material such as lumber which is likely to shift or settle in transit, it is customary to bind the material to the transporting conveyance with a chain. To impart tension or a binding force to the ends of the binding chain, load binders are commonly employed. Such devices, in general, consist of mechanism operable to pull the ends or parts of the chain toward each other to take up slack and create a binding force for holding the load securely in position. To take up slack due to settling of the load without releasing the binding tension on the chain and to prevent breakage of the chain where the load is subjected to shock, springs have been employed for the purpose of yieldingly sustaining the tension on the load binding chain. However, the arrangements heretofore proposed have involved the location of the springs either in the binding chain or on the load binder in a position where they are subjected to rough usage and damage of a nature likely to result in their disconnection or breakage. In addition, conventional load binders have presented objectionable features in that by reason of the rough usage to which they are subjected, they are apt to get out of order and in need of repair, and due to complexity of construction, the necessary repairs are made at best with extreme difficulty.

One of the principal objects of this invention is to provide an improved load binder which is simple in design, is easily disassembled for purposes of repair, is ruggedly constructed so that it is capable of withstanding rough usage, and has built-in resilient features for yieldingly sustaining the tension on a load binder chain with which it is associated. To this end, there is provided a frame or housing member which completes the connection of the binder to the ends of a binding chain. One connection to one end of the chain comprises a compressible spiral spring which is housed and protected by the frame. The spring is compressed when the binder applies force to the binding chain and will expand when the load settles, thereby maintaining the desired tension on the binding chain, and will compensate for forces created by subjection of the load to shock, thereby preventing breakage of the binding chain. The other connection to the other end of the binding chain comprises a pull chain assembly in the nature of a sprocket chain which is trained over a sprocket wheel mounted on a shaft carried in the frame. The mechanism for imparting rotation to the sprocket wheel to exert a binding force includes a manually operable lever pivoted to the shaft carrying the sprocket wheel and ratchet mechanism for

2

rendering the lever operable to impart rotation to the sprocket wheel. The housing frame is so arranged that it completely houses and protects both of the connections to the binding chain.

5 A further object of this invention is to provide a load binder with an improved arrangement of parts for training and stripping a sprocket chain with respect to a sprocket wheel.

10 A still further object of the invention is to provide an improved arrangement of ratchet and operating mechanism for controlling the operation of a sprocket wheel employed to impart forces to the ends of a binding chain.

15 Another object of the invention is to provide an improved ratchet mechanism comprising a pawl which is mounted for rectilinear movement into operative engagement with the ratchet teeth of a ratchet wheel, the pawl and ratchet teeth having abutting surfaces located in a plane inclined with respect to a radius of the ratchet wheel, the angle of inclination being in such direction as to produce a component force which is applied to the pawl in a direction tending to maintain the pawl in engagement with the ratchet teeth.

20 Still another object of the invention is to provide an improved arrangement of operating mechanism for a load binder in which all of the force-exerting parts may be removed from the housing therefor upon removal of a single locking pin.

25 Other objects and advantages of the invention will become apparent from the following description.

In the drawing there is shown a preferred embodiment of the invention. In this showing:

30 Figure 1 is a plan view of a load binder constructed in accordance with the principles of this invention and in which a portion of the operating handle therefor is illustrated as being broken away;

35 Figure 2 is an elevational view of the load binder shown in Figure 1, certain of the parts being omitted;

40 Figure 3 is a fragmentary sectional view taken substantially along the line III—III of Figure 1;

45 Figure 4 is a fragmentary sectional view taken substantially along the line IV—IV of Figure 1;

50 Figure 5 is an enlarged fragmentary view of the ratchet wheel and pawls similar to that of Figure 4 illustrating the operating pawl and locking pawl in their operative positions with respect to the ratchet wheel;

55 Figure 6 is a longitudinal sectional view of a modified operating mechanism for controlling the operation of the locking pawl; and

60 Figure 7 is an end elevational view looking from the left of Figure 6.

Referring to Figure 1 of the drawings, the numeral 1 designates as a whole a load binder provided with grab hooks 2 and 3 which provide, re-

spectively, connections by which the binder may be secured in position to impart a binding force to a binding chain. The connections of the grab hooks 2 and 3 are made in conventional fashion to a binding chain or the like so as to be effective to remove slack therefrom and apply a tightening force thereto. The binder 1 includes a frame 4 which functions to house and protect the operating parts of the binder, and which further functions to complete a mechanical connection to the grab hooks 2 and 3 in a manner to be described.

The frame 4 is rigidly constructed and is preferably formed of malleable iron or cast steel. The frame 4 comprises side walls 5 and 6 connected together in spaced relation by end walls 7 and 8. The end walls 7 and 8 are provided with openings 9 and 10 axially aligned longitudinally of the frame 4 and through which the connection to the grab hooks 2 and 3 are made so that a binding force created by the binder 1 will be applied in a straight line to the grab hooks 2 and 3.

The connection of the grab hook 2 to the frame 4 comprises a swivel connection 11 including an eye-bolt 12 having a shank 13 extending inwardly through the opening 9 in the end wall and turnable therein. A nut 14, with a suitable washer, is threaded on the inner end of the shank 13 and a spiral spring 15 is positioned between the washer and the inner surface of the end wall 7, the ends of the spring 15 bear against the inner surface of the end wall 7 and the washer positioned against the nut 14. When the binder applies a force tending to move the grab hooks 2 and 3 toward each other, the shank 13 will move outwardly through the opening 9 and partly compress the spring 15. The compression of the spring 15 will operate to yieldingly maintain the tension on the binding chain when the load to which it is applied settles into position. In addition, the spring 15 will compensate for shock applied to a load held by a binding chain, and will be effective to reapply the binding force after the shock has passed without breaking the binding chain. From Figures 1 and 2 it will be noted that the frame 4 completely houses and protects the spring 15 in such manner that rough usage will be incapable of damaging or disconnecting the spring 15. I prefer to utilize a spring of such strength that it will not be fully compressed by the usual stresses to which it is subjected by the binder.

The connection of the grab hook 3 to the frame 4 includes a swivel connector 16 which is secured to an end of a sprocket chain 17 which extends inwardly through the opening 10 in the end wall 8, and is trained over sprocket wheel 18. The sprocket wheel 18 is formed integrally on an annulus 19 which also carries a ratchet wheel 20 integral therewith. The annulus 19 is journaled on a shaft 21 which extends transversely of and through the side walls 5 and 6 and has its ends respectively supported in such side walls. By reason of the fact that the sprocket wheel 18 and ratchet wheel 20 are formed integrally with the common annulus 19, the annulus and the wheels will rotate as a unit. A tapered dowel pin 22 is employed for the purpose of securing the shaft 21 in position with respect to the frame 4.

As best shown in Figures 2 and 3, the active portion of the sprocket chain 17 extends through the opening 10 in a direction so as to engage tangentially with the sprocket wheel 18. When

the chain 17 is initially applied to the wheel 18, its free end 23 is directed downwardly into engagement with a training lug 24. The training lug 24 operates to maintain the chain 17 in engagement with the sprockets on the wheel 18 as illustrated in Figure 3. As the sprocket wheel 18 rotates, it will carry the chain 17 around the shaft 21, until the links of the chain engage with the surfaces 25 on stripping lug 26 in the event that such links have not become disengaged from the cogs as illustrated. As the motion of the chain links is continued, the surface 25 will operate to strip the chain links out of engagement with the cogs on the sprocket wheel 18. As best shown in Figure 1, a pair of stripping lugs 26 are provided in the frame 4, such lugs being arranged to straddle the cogs on the sprocket wheel 18. As shown in Figure 3, the arrangement of the training lugs 24 and stripping lugs 26 is such that the chain 17 is maintained in engagement with approximately 180° of the sprocket wheel 18 at all times.

Attention is particularly invited to the fact that the openings 9 and 10 are in direct alignment with the portion of the chain 17 moving into engagement with the sprocket wheel 18 and that the bolt shank 13 extends axially along the line of the openings 9 and 10. In this manner the forces applied to the grab hooks 2 and 3 are applied in a straight line and are effectively transmitted through the structure of the frame 4.

In order to rotate the sprocket wheel 18, a handle yoke or operating lever 27 is provided for applying torque to the ratchet wheel 20. As best shown in Figure 1, the lever 27 is bifurcated to provide fork arms 28 and 29. The arms 28 and 29 straddle the sprocket wheel 18 and the ratchet wheel 20 and have their ends journaled on the shaft 21 at points adjacent the side walls 5 and 6. The body of the lever 27 is provided with a cylindrical opening for the reception of a cylindrical operating pawl 30 which is movable axially and rectilinearly into operative engagement with the ratchet wheel 20. A spring 31 urges the pawl 30 into engagement with the ratchet wheel 20. The pawl 30 has an extension 32 which is connected to one end of a wire rod 33 having its other end hooked to an arm 34 of a bell crank lever pivoted at 35 to the handle 27. The other arm 36 of the bell crank lever may be moved manually to move the pawl 30 out of engagement with the ratchet wheel 20 against the bias of the spring 31. Referring to Figure 2, it will be noted that the pawl 30 will be cammed away from the ratchet wheel 20 against the action of the spring 31 by the action of the ratchet teeth 37 against the end of the pawl 30 upon movement of the lever 27 in a clockwise direction. When the lever 27 has moved sufficiently for the pawl to pass over one of the ratchet teeth 37, the pawl 30 will engage with the next succeeding ratchet tooth, and upon movement of the lever 27 in a counter-clockwise direction, the ratchet wheel 20 will be rotated counter-clockwise. This rotational movement will be imparted to the sprocket wheel 18 to move the end of the chain 17 connected to the swivel 16 to the left as viewed in Figure 1. This will tighten and apply a binding force to the load chain to which the hooks 2 and 3 are connected.

To lock the ratchet wheel 20 against movement in a clockwise direction, a cylindrical locking pawl 38 is mounted for axial and rectilinear movement in a cylindrical opening formed in the

housing 4. A spiral spring 39 urges the pawl 38 into operative engagement with the ratchet wheel 20. The pawl 38 is provided with an extension 40 which is connected to a grasp 41 by which the pawl 38 may be moved manually against the action of its spring out of operative engagement with the ratchet wheel 20. The ring grasp 41, when the pawl 38 is in operative engagement with ratchet wheel 20, is received in a slot 41a which ring sliding in the slot acts as a guide to keep the holding surface of the end of the pawl in proper alignment for engaging with the teeth of the ratchet wheel. When it is desired to hold the pawl out of engagement with the ratchet wheel, the grasp is moved to compress the spring 39 and the ring is then turned so that it may rest on the end 41b of the housing. When the lever 27 is moved in a counter-clockwise direction to impart rotation to the ratchet wheel 20, the pawl 38 will be cammed to the left by a ratchet tooth 37, and when the ratchet wheel 20 moves sufficiently far, the pawl 38 will be urged by the action of spring 39, to the position shown in Figure 2, in which the pawl will again be operative to prevent rotation of the ratchet wheel 20 in a clockwise direction.

As best shown in Figure 5, the pawls 30 and 38 are provided with inclined surfaces 42 and 43, respectively, for engagement with cooperating surfaces 44 on the ratchet teeth 37. The surfaces 42 and 43 and the ratchet teeth surfaces 44 are so arranged that when they are in operative abutting engagement, a component force will be produced, tending to move the pawl toward the center of the ratchet wheel 20. This structure and its action will be best understood by referring to the enlarged showing of Figure 5, in which the ratchet wheel 20 is illustrated in connection with the lever pawl 30 and the locking pawl 38. In this showing, it will be noted that the pawl engaging surfaces 44 on the ratchet teeth 37 are in planes parallel to and spaced from a diameter of the shaft 21 on which the ratchet wheel 20 is mounted. It will also be noted that the horizontal center-lines of the pawls 30 and 38 are above the center of the ratchet wheel 20. The offset relation of the pawl center-lines and ratchet wheel center is desired in order to secure a locking action between these parts. In this manner the surfaces 44, are angularly inclined with respect to any radius of the ratchet wheel 20 which may be drawn to intersect such surfaces. These surfaces are inclined in the direction in which a load on the chain 17 tends to rotate the ratchet wheel 20. By reason of this angular inclination, when the surfaces 44 are in engagement with the inclined pawl surfaces 42 and 43, there will be produced a component of force on the pawls so engaged which will assist the action of their biasing springs and will be effective to lock the pawl in operative engagement with the ratchet wheel. This action is very effective in preventing movement of the pawl out of operative engagement with the ratchet wheel. The greater the load or tension on the hooks 2 and 3, the forces transmitted are such that they tend to lock in engagement the pawl 38 to ratchet tooth 37 more securely, preventing them from becoming disengaged under any operating conditions. This is of very great importance both as a safety measure for preventing accidents to men, and to eliminate the possibility of the load binder loosening its tension and hold on the chain, which would allow the load of transported materials to shift or fall off the vehicle.

The pawls 30 and 38 are of identical construction and of equal length so that the same pawl may be used as an operating pawl on the lever 27 or as a locking pawl on the frame 4. In mounting the pawls, as shown in Figures 4 and 5, it will be noted that the pawl 30 is positioned so that its ratchet engaging surface 42 faces in an upward direction, and the pawl 38 is positioned so that its ratchet engaging surface 43 faces in an upward direction. The positioning of the pawls in this manner provides a phase reversal necessary by reason of the location of the pawls 30 and 38 on diametrically opposite sides of ratchet wheel 20. The pawl 38 functions as a locking pawl and the engagement of its surface 43 with a ratchet tooth surface 44 is effective to prevent rotation of the ratchet wheel 20 in a counter-clockwise direction. The pawl 30 functions as an operating pawl and the engagement of its surface 42 with a ratchet tooth surface 44 is effective to impart rotation to the wheel 20 upon rotation of the lever 27 carrying the pawl 30 in a clockwise direction.

In the showings of Figures 2 and 4, the pawl surfaces 42 and 43 are illustrated as being out of engagement with the ratchet teeth surfaces 44 in order to more clearly illustrate the structure of the parts respectively carrying such surfaces.

The action and operation of the pawls 30 and 38 will be best understood by referring to the enlarged showing of Figure 5. In this showing, the pawl 38 is shown in the position it occupies when it is effective to prevent rotation of the wheel 20, and the pawl 30 is shown in the position it occupies when it is effective to impart rotation to the wheel 20. In these positions it will be noted that the surfaces 42 and 43 are in abutting engagement with ratchet tooth surfaces 44. As the lever 27 is moved in a clockwise direction to move the pawl 30 from the position shown in full lines to a position indicated by the dotted lines in Figures 5, the surface 45 will operate to cam the pawl 30 outwardly against the action of its biasing spring 31. When the lever 27 has moved sufficiently far, the bias on the pawl 30 will be effective to move the cam inwardly into engagement with the next succeeding surface 45 so that subsequent rotation of the lever 27 in a counterclockwise direction will be effective to engage the pawl surface 42 with another ratchet surface 44 and to impart rotation to the wheel 20. As the wheel 20 is rotated in a counter-clockwise direction the surface 45 in engagement with the pawl 38 will cam the pawl 38 outwardly until a ratchet tooth moves out of engagement with such surface whereupon the pawl 38 will move inwardly until it is stopped by another surface 45 and be again effective to prevent rotation of the ratchet wheel in a clockwise direction. It will thus be seen that the pawl 38 is operative to prevent all clockwise rotation of the ratchet wheel 20 except that necessary to engage the surfaces 43 and 44.

Figures 6 and 7 illustrate a modified construction for operating the pawls which may be used to withdraw the pawls against the action of their biasing springs. Figures 6 and 7 show the application of the modification to the locking pawl 38. In this showing, the extension 40 is provided with an opening at its end for the reception of a pin 46 which projects outwardly through a slot 47 formed in the housing 4. In normal operation, engagement of the pin 46 with the sides of the slot 47 will function to guide the rectilinear and axial movement of the pawl to

which it is connected and to prevent rotation of the pawl during such movement. When it is desired to move the pawl to an inoperative position with respect to the ratchet wheel 20, it is merely necessary to grasp the pin 46 and move it manually to the left, as viewed in Figure 6, and rotate it to a position out of alignment with the slot 47 as indicated by the dotted lines in Figure 7. In this position, the pin will engage with the end 48 of the housing 4 and be prevented from movement by its biasing spring to an operative position with respect to the ratchet wheel 20.

From the foregoing, it will be noted that the frame 4 operates to provide a housing for all of the operating parts of the binder. Attention is particularly invited to the fact that the operating parts may be readily removed by removal of the locking pin 22. Removal of the locking pin 22 will permit the shaft 21 to be moved out of engagement with the forked arms 28 and 29 of the operating lever 27, and out of engagement with the annulus 19 carrying the sprocket wheel 18 and the ratchet wheel 20. This will enable the sprocket wheel, ratchet wheel, chain and handle to be disassembled.

The manual adjustment provided by the parts 36 and 41 enables the pawls 30 and 38 to be withdrawn from operative engagement with the ratchet wheel 20, which then may be manually adjusted to position the sprocket chain 17. It will also be noted that when the annulus 19 is disassembled as described above, the pawls 30 and 38 may be readily removed upon disconnecting their connections with the parts 36 and 41. The hook 2 may be removed at any time by removing the nut 14 which is normally held against rotation by the cotter pin 50. It will thus be seen that there is provided a load binder having a rugged construction in which all of the operating parts are protected and housed by the frame 4, and in which the operating parts are constructed and arranged in a simple manner so that they may be readily removed and replaced if necessary. Also the housing 4, in addition to providing protection for the parts furnishing the connections to the grab hooks 2 and 3, further functions to complete the connection between such grab hooks.

While I have illustrated and described one particular embodiment of my invention, it will be understood that this is merely by way of illustration, and that various changes and modifications may be made within the contemplation of my invention and under the scope of the following claims.

I claim:

1. A load binder comprising spaced connectors for imparting a binding force to the ends of a chain or the like, and means mounting said connectors including a frame, a spring connected with one of said connectors and with said frame for deflection in accordance with the binding force applied, a sprocket chain secured to the other of said connectors, a sprocket wheel journaled on said frame and having said chain trained thereon, ratchet mechanism for operating said wheel comprising a pawl mounted for rectilinear movement to an operative position and having an end surface normal to its path of rectilinear movement and a ratchet tooth engaging side surface extending inwardly from one edge of said end surface, said pawl end and side surfaces intersecting at an angle slightly less than a right angle, and a rotatable ratchet wheel having a plurality of ratchet teeth at spaced in-

tervals along its periphery, each of said teeth having a locking surface extending inwardly from the ratchet wheel periphery and positioned in a plane parallel to and closely adjacent to a radius of the said ratchet wheel for locking engagement with said pawl side surface, and a camming surface intersecting with the inner edge of and normal to said locking surface for camming engagement with said pawl end surface, each of said camming surfaces intersecting the periphery of the ratchet wheel at a point closely adjacent the outer edge of the locking surface on an adjacent tooth.

2. A load binder comprising spaced connectors for imparting a binding force to the ends of a chain or the like, a housing frame having side walls positioned on opposite sides of a line extending between said connectors and a pair of end walls connecting said side walls, said end walls having openings therein aligned with said line, a connection for one of said connectors with said frame including a bolt extending through one of said openings, a collar on said bolt spaced from the end wall containing said one opening and positioned between said side walls, and a spring between said collar and said last-named end wall which is compressible to permit movement of said collar toward said last-named end wall, and a connection for the other of said connectors comprising a shaft extending transversely of said walls, a sprocket wheel mounted on said shaft, a sprocket chain trained on said wheel and extending through the other of said openings, said sprocket chain having a connection with said other connector at a point spaced from said frame, and ratchet means for operating said sprocket wheel to decrease the distance between said connectors and thereby apply a binding force thereto comprising a pawl mounted for rectilinear movement to an operative position and having an end surface normal to its path of rectilinear movement and a ratchet tooth engaging side surface extending inwardly from one edge of said end surface, said pawl end and side surfaces intersecting at an angle slightly less than a right angle, and a rotatable ratchet wheel on said shaft and having a plurality of ratchet teeth at spaced intervals along its periphery, each of said teeth having a locking surface extending inwardly from the ratchet wheel periphery and positioned in a plane parallel to and closely adjacent a radius of the said ratchet wheel for locking engagement with said pawl side surface, and a camming surface intersecting with the inner edge of and normal to said locking surface for camming engagement with said pawl end surface, each of said camming surfaces intersecting the periphery of the ratchet wheel at a point closely adjacent the outer edge of the locking surface on an adjacent tooth.
